UNITED STATES PATENT OFFICE.

JAMES A. NOLAN, OF BOWERSTON, OHIO.

ТИЛТИНГ ПЛАТФОРМ ФОР МИНЕ-КАР ДУМПС.

1,254,621.

Specification of Letters Patent. Patented Jan. 22, 1918.

Application filed September 30, 1916. Serial No. 123,148.

To all whom it may concern:

Be it known that I, JAMES A. NOLAN, a citizen of the United States, residing at Bowerston, in the county of Harrison and State of Ohio, have invented new and useful Improvements in Tilting Platforms for Mine-Car Dumps, of which the following is a specification.

This invention relates to mine car safety devices and particularly to devices used with the dumps associated with drift mines and the like.

One of the objects of the invention is to provide means for operating the car control mechanism by the tilting platform or dump.

According to my invention the tilting platform may, when approaching a horizontal position cause the car-control mechanism to feed a car automatically toward the platform, but when the platform is tilting to dump, the car-control mechanism will assume such position that the liability of a car feeding into the space behind the tilting platform will be avoided.

Besides the above my invention is distinguished in the use of a lost motion device between the platform and the car control mechanism so that the kinetic energy of the moving car thereon may be relied on to operate the car control mechanism.

In the drawings:—

Figure 1, is a plan view of a portion of a track and dump to which my invention is applied.

Fig. 2, is a side elevation of the same,

Fig. 3, is an end elevation partly in section and partly in elevation.

Figs. 4 and 5 are diagrammatic views of the car in two positions.

The numerals 1 and 2 designate the two rails of a track between which are arranged suitable bearings supporting a rock shaft 3. Arranged upon the rock shaft 3 at spaced points are sets of levers 5 and 6 for operating the stops 7, 8, 9 and 10. Springs 16, 17, 18 and 19 are provided to compensate for shocks.

On one end of the shaft 3 adjacent to one edge of the tilting platform 20, is a double crank arm 21 the ends of which are connected to a similar double crank arm 22 by links 23 and 24. The center portion of the arm 22 is rigidly secured to a rock shaft 25 supported by suitable bearings 26 and 27, the latter being carried by a timber 28 which in turn forms a stop for the platform.

The rock shaft 25 has one end bent at an angle so as to continuously engage a slot 29 in an arcuate bracket 30, secured to, but depending from the under surfaces of the platform.

To complete my invention I have shown slidably mounted upon the rails 31 and 32 of the platform curved abutments 33 adapted to engage the wheels of the car and arrest rectilinear movement thereof. To compensate for the shock I provide coil springs 34 that encircle rods 35 each of which has a pivotal connection with one of the abutments as illustrated at 36. Each rod 35 is slidably mounted in a bearing 37 supported by the rail.

Any suitable mechanism may be provided for moving the abutments out of engagement with the wheels of the car for allowing the same to pass onto the continuation 38 of the main track but for the purpose of illustration I have illustrated a toggle lever mechanism 39 operated in any suitable manner.

To assure the return of the car and platform to its normal position after the dumping operation the platform is pivotally connected off center to a supporting structure 40 as clearly shown in the diagrammatic view in Figs. 4 and 5 while a weight 41 is attached to the platform adjacent one end thereof. In the operation of the apparatus a car is released upon the rails 1 and 2 by operation of the control mechanism. The car immediately picks up speed and the momentum thereof is great enough to cause the platform to turn about its pivot when the wheels strike the abutments 33, that is to say the rectilinear motion of the car is converted into circular motion by the engagement between the abutments 33 and the front wheels of the car. Just before this circular motion of the platform and the car is completed one end wall of the slot 39 engages and operates the rock shaft 25 which through the medium of the arms 21 and 22 and the cranks 23 and 24 give a partial rotation to the shaft 3 for moving the rear stops 7 and 8 away from the rails and the front stops 9 and 10 toward the

rails so as to allow the next car to take up its proper position.

After the coal has been dumped, the off-center manner of supporting the platform 5 acting conjointly with the weight 41 causes the platform and car to move toward a horizontal position. When the position of the platform and car toward a horizontal position has reached a pre-determined angle, 10 engagement is brought about between the remaining end wall of the slot and the rock shaft 25 thereby allowing the kinetic energy of the returning dump to operate the control mechanism for allowing another 15 car to pass upon the platform.

At this point I wish to call attention to the fact that the rails 1 and 2 are inclined so that when the front stops 9 and 10 are 20 operated a loaded car will obtain enough momentum to pass upon the dump and displace the empty car.

It is to be understood that while all of the several features of my improved machine have special coöperations with one 25 another and together constitute a particularly effective mechanism for the purpose in view either of these features may be applied in other relations and I therefore desire to cover the combination present in the 30 several parts of my improved invention

whether employed in the general organization shown or elsewhere.

What I claim is:—

1. In a device of the class described, the combination with an operating shaft, of a 35 car-control mechanism and a tilting platform, of a rock shaft below the operating shaft and provided with a crank arm at one end, link connections between the operating shaft and the rock shaft and an arm depending from the platform and provided with an arcuate slot engaged by the crank arm of the rock shaft. 40

2. In a device of the class described, a 45 car-control mechanism comprising a pair of oppositely operating car stops, an operating shaft connected to said car stops, an arm on said shaft having oppositely projecting ends, a rock shaft below the operating shaft and having an arm fixed thereto with oppositely projecting ends, links connecting pairs of oppositely connecting ends on said shafts, a right angular projection on the free end of the rock shaft and a depending arm on the tilting platform, said 50 arm having an arcuate slot engaging the free end of said rock shaft. 5

In testimony whereof I affix my signature.

JAMES A. NOLAN.
